JAKOB SULZER, OF WINTERTHUR, SWITZERLAND.

REVERSING-VALVE MECHANISM FOR INTERNAL-COMBUSTION MOTORS.

No. 880,051.

Specification of Letters Patent.

Patented Feb. 25, 1908.

Application filed December 8, 1905. Serial No. 290,915.

To all whom it may concern:

Be it known that I, JAKOB SULZER, engineer, a citizen of the Swiss Republic, residing at Winterthur, 97 Langgasse, Switzerland, have invented certain new and useful Improvements in Reversing-Valve Mechanism for Internal-Combustion Motors; and I do hereby declare the following to be a full, clear, and exact description of the invention, such as will enable others skilled in the art to which it appertains to make and use the same.

This invention relates to an improved reversing valve mechanism for that kind of internal combustion motors wherein after cutting off the supply of combustible in the working cylinder gaseous pressure fluid is introduced so as to effect the reversal or the starting of the motor.

The invention consists in an arrangement of the valve mechanism whereby the eccentric or cams that operate the reversing valve and the combustible supply valve are shifted simultaneously by an actuating device in such manner that while the one eccentric or cam and its corresponding valve are put out of action the other cam is made to actuate its corresponding valve.

An arrangement for carrying out the invention is shown on the accompanying drawing which is a longitudinal section through the working cylinder. In the cylinder head of the working cylinder *a* are provided two valves *b*, *c* of which the valve *b* serves for admitting the combustible mixture into the cylinder, while valve *c* serves for introducing a supply of gaseous fluid under pressure. For actuating valve *b* there is mounted on the cylinder head a two-armed lever *d* and for actuating valve *c* there is provided a two-armed lever *e*. These levers, which work on a horizontal shaft are connected to the rods of the valves and carry at their other ends rollers *f* and *g* respectively. For actuating the lever *d* there is provided a cam plate *h* beneath the roller *f* thereof and in the same plane therewith and for actuating lever *e* there is provided a cam plate *i* under the roller *g* and in the same plane therewith. These cam plates are mounted on the periphery of an eccentric *l* fixed on a valve motion shaft *k* and they have each two operating bosses *h'*, *h''* and *i'*, *i''*, as also an inoperative part *h³* and *i³* situated between the bosses. To the cam plate *h* is pivoted a link *m* which is connected

to the one arm of a two-armed lever *n* whose other arm is connected by a link *o* to the pin of a crank disk *p*, while to the cam plate *i* is pivoted a link *q* which is connected to the one arm of an elbow lever *r* mounted loose on the axis of lever *n* and having its other arm also connected by a link *s* to the pin of the crank disk *p*. On the shaft of this crank disk is fixed a worm wheel *t* with which gears a worm *u* whose shaft has a hand wheel *v*. The action of this reversing mechanism is as follows:

The drawing shows the motor arranged for the one direction of motion for instance for the forward motion. The valve motion shaft imparts by means of its eccentric *l* a to and fro motion to the cam plates *h* and *i*; by means of the boss *h'* bearing the roller *f*, the combustible supply valve is opened by the lever *d*, while the supply valve *c* remains closed, because the roller *g* of its actuating lever *e* is situated over the inoperated part *i³* of the cam plate *i*, this part being so formed as not to move the lever during its rocking motion.

For reversing the motion of the motor the worm *u* is rotated by means of the hand wheel *v* so as to turn the worm wheel *t* and crank disk *p* in the direction of the arrow so that the crank pin is made to move from the position I into the position II. By this means the cam plates are so shifted upon the periphery of the eccentric *l* that the roller *g* of lever *e* comes in contact with the boss *i²* while roller *f* of lever *d* is brought over the inoperative part *h³*, so that on the rotation of the shaft *k* and eccentric *l* and the resulting rocking motion of the cam plates the pressure fluid supply valve *c* will now be opened during the upstroke of the piston, while the valve *b* on the other hand will remain closed, as the lever *d* is not actuated by the part *h³* of its cam plate. The valve *c* being opened, pressure fluid enters the cylinder so as to reverse the motion of the motor or to start it in the reverse direction. The crank disk *p* is now turned farther in the same direction until the crank pin attains the position III; by this means the boss *h²* of the cam plate *h* is brought to bear against the roller *f*, while the inoperative part *i³* is brought under the roller *g* so that on the continued rocking motion of the cam plates, the combustible supply valve *b* will now be opened and the valve *c* will remain closed.

For again reversing the motion of the motor, the crank disk is again turned in the same direction until the crank pin is in the position IV. The cam plates are thereby so shifted upon the eccentric *l* that the cam *i* bears with its boss *i'* against the roller *g* while the inoperative part *h²* of *h* comes under roller *f* so that on the cam plate being rocked the valve *c* will be opened during the upstroke of the piston, while the valve *b* remains closed as the lever *d* is not actuated, pressure fluid now entering the cylinder, the piston is in the first instance brought to a standstill, and then has its motion reversed. The crank disk is then again turned until the crank pin assumes the position I (as on the drawing) when the combustible-supply valve *b* will be opened and valve *c* will remain closed.

Having thus described the nature of this invention and the best way I know of carrying the same into practical effect, I claim:

1. An internal combustion or explosion motor having a reversing valve and a fuel-supply valve, in combination with oscillating cam-plates for actuating said valves, and means for shifting the oscillating cam-plates to an intermediate position in which they do not move the said valves, and into two extreme positions, corresponding to the two directions of movement of the motor, in

which they do move the said valves, substantially as described.

2. An internal combustion or explosion motor having a reversing valve and a fuel-supply valve, in combination with oscillating cam-plates for actuating said valves, the said cam-plates being so mounted that they are capable of being shifted to an intermediate position in which they do not move the said valves, and into two extreme positions, corresponding to the two directions of movement of the motor, in which they do move the said valves, and means for simultaneously shifting the said cam-plates from a position in which the fuel-admission-valve is operated by this cam-plate and the reversing valve is not operated, to a position in which the reversing valve is actuated by this cam-plate and the fuel-admission-valve is not operated, and then into a position in which the fuel-admission valve is operated at a time corresponding to the reversed movement of the engine and the reversing valve is not operated, substantially as described.

In testimony whereof I have affixed my signature, in presence of two witnesses.

JAKOB SULZER.
